COIN RECEPACLE

Walter J. Herschede and Walter Eberhardt, Cincinnati, and William Foy Herschede, Forestville, Ohio, assignors, by mesne assignments, to International Vehicular Parking, Ltd., Washington, D. C., a corporation of Delaware

Application November 12, 1937, Serial No. 174,178

1 Claim. (Cl. 232—4)

This invention relates to a coin-receiving receptacle and more particularly to a coin receptacle adapted to be utilized in parking meters and the like.

5 The principal object of this invention is to provide a simple and relatively cheap coin receiving or collecting receptacle which may be removably placed in various instruments or devices such as parking meters, telephone boxes 10 and the like, and which cannot be tampered with, without that fact being readily evident.

A further object of this invention is to provide a coin receptacle having novel means thereon to receive a seal so that the same may be effectively sealed to guard against unauthorized 15 opening of the receptacle.

With the above and other objects in view, the invention consists in general of certain novel details of construction and combination of parts 20 hereinafter fully described, and illustrated in the accompanying drawing.

These and other objects are attained by the means described herein and disclosed in the accompanying drawing, in which:

25 Fig. 1 is a top view of the coin receptacle.
Fig. 2 is a cross-section taken on line 2—2 of Fig. 1.

In the embodiment of the invention as shown in the present drawing, there is provided a box, 30 preferably made of molded material, comprising side walls 10, a bottom 11, and end walls 12, and a removable cover or top 13. The box is provided with integral corner supports or braces 14 which also support the cover 13. The supports 35 14 extend to near the top of the receptacle and terminate at a distance from the top which corresponds to the thickness of the cover 13. The box may have an offset 15, or may be made in any desired shape. The bottom 11 has a plurality of integrally formed lugs or legs 16 which serve to maintain the box in alignment with a coin-chute in a parking meter or the like and also serve as guard members for a paper seal which may be placed around the box between the 40 legs 16 and lugs 19 and 21 on the cover 13, for a purpose to be explained later.

The cover 13 is adapted to fit within the side walls 10 and end walls 12 and be supported by the corner supports 14. At its forward edge the 45 cover 13 is provided with an integral handle 17 and a downwardly extending lug or shield 18. An upwardly extending lug or rib 19 is provided on the upper surface of the cover 13 parallel to the handle 17 but positioned therefrom a substantial distance. One corner of the cover 13

is cut off as at 20 and a complementary formation is provided at the corner of the box so that the cover 13 can only be placed on the box in one position.

Opposite the lug 19, on the cover 13, there is 5 provided an integral upwardly extending lug 21. Adjacent to the lug 21 is an aperture 22 extending through cover 13, for the passage of coins therethrough. Integrally formed with the cover 13, and extending downwardly from the aperture 22, is a coin chute 23 comprising a slanting member 24, and a slotted lip 25. A plurality of slots (not shown) are provided in the lip 25. A rod or pin 26 is mounted in the shoulders of the lip 25 and movably mounted upon this pin 10 26 and inserted in the slots, are a plurality of trapezoid shaped guard members 29 or fingers, which are weighted so that their centers of gravity are at 30, thereby holding the tip 31 normally against the edge of the slanting member 20 24 when the cover is in position on the coin receptacle. The guard members 29 effectually prevent the removal of coins from the coin receptacle by turning it upside down and attempting to shake coins out through the aperture 22 25 in the cover 13.

It will be understood that the improved coin receptacle may be effectively sealed against unauthorized tampering by placing a strip of paper around the coin receptacle between lugs 21 and 19 on the cover 13 and between the oppositely disposed pairs of legs 16 on the bottom 11 and gluing the paper ends. Any attempt to slide the paper seal off the box will be prevented by the lugs 21 and 19 and legs 16 and if the paper seal 35 is otherwise tampered with, it will be readily obvious.

In actual practice, a service man would be given a definite number of boxes, each having an encircling sealing band positioned thereon, between 40 the lugs 16, 19 and 21. The seal is intended to tightly contact or fairly closely follow the walls and cover of the box. The service man's duties include the exchange of empty and coin-containing 45 similarly sealed boxes in certain parking meters or the like assigned to him. The sealed boxes, containing money, are to be delivered to the person authorized to open same, and the seal is to assure delivery of the coin-containing boxes to such authorized person, without removal of 50 any of the contents of the boxes. Therefore, the paper seal must be tight enough to prevent partial lifting of the lid without injuring the seal. Therefore, the lug or shield 18 must be wide enough and long enough, to prevent the end of 55

the lid carrying the handle 17, from being lifted relative to the box, and within the elastic limit of the paper sealing band 40, to permit pilfering of coins from the box without so rupturing or mutilating the sealing band as to be readily observable.

Also, it must be impossible for the annular sealing band to be slid endwise of the box so the lid may be freely opened and after closing of the lid, again slide the sealing band back into its original position. The lugs 16 and ribs or lugs 19 and 21 on the cover prevent such separation of the band and box.

Incidentally, it should be noted that boxes, molded of such materials as "Bakelite" and similar formaldehyde or phenol condensation and synthetic resin products that are desirable because of the ease and economy of manufacture thereof into such boxes, are inherently incapable of adhesion by the ordinary, cheaper mucilages and glues of commerce and therefore it is not practical to merely paste or glue a sealing strip over the top and attach the strip to the side walls of the box. While there are some adhesives that will function for securely fixing the paper strips to boxes of the character used and shown herein, such glues are too expensive and involve such factors of solvents, volatility and the like that

for practical reasons it is not economically desirable or feasible to use such materials or method of sealing the lids on the boxes.

The foregoing detailed description has been given for clearness of understanding only and no unnecessary limitations should be understood therefrom, but it should be construed as broadly as permissible in view of the prior art.

What is claimed is:

In a device of the character described, a coin box having spaced lugs on its exterior; a removable top for said box having lugs thereon lying in parallel planes with said box lugs and also having a shield member contacting an inner portion of the box to prevent sliding the top off the box upon slight lift, and in addition having a coin receiving aperture in a position outside of the region defined by the spaced lugs on top of the box and having chute means extending into the box from the aperture adjacent another inner portion of the box also to prevent sliding the top off the box; and a rupturable sealing band encircling box and top aligned in a position between the lugs of box and top to maintain the top on the box against unauthorized removal of the same. 25
